The ornamental design for a four wheeled vehicle, as shown and described.

DESCRIPTION

FIG. 1 is a left side, front, perspective view of a four wheeled vehicle showing my new design;

FIG. 2 is a left side, rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

A view of the bottom is omitted as the bottom is devoid of surface ornamentation and forms no part of the claimed design.
